UNITED STATES PATENT OFFICE.

DWIGHT WHEELER AND DAVID C. WHEELER, OF BRIDGEPORT, CONN.

METHOD OF MANUFACTURING HATS.

SPECIFICATION forming part of Letters Patent No. 286,244, dated October 9, 1883.

Application filed January 24, 1883. (No model.)

To all whom it may concern:

Be it known that we, DWIGHT WHEELER and DAVID C. WHEELER, both of Bridgeport, Fairfield county, Connecticut, have invented 5 an Improved Method of Manufacturing Hats, of which the following is a specification.

Our invention is an improved mode of manufacturing hats, whereby we reduce the cost of material and manufacture, are enabled to 10 use firmer material than that usually employed, and secure a greater variety in the product.

In the drawings, Figure 1 is a cross section 15 illustrating a hat made in accordance with our improvement. Fig. 2 is a section of the brim-piece detached, and Fig. 3 a section of the crown-piece detached.

It is customary, in making fur, felt, cloth, and other hats with covering fabrics applied 20 to the frame, to first mold the frame comprising the crown and brim in one piece, and then to apply the covering and lining. This necessitates the use of a very open, pliable material for the frame, but it must be of such 25 weight as to impart the desired thickness at the band portion. Moreover, it is expensive and difficult to apply the lining and covering pieces to the crown and brim, especially when 30 one colored fabric is to be applied to the crown and another to the brim. Sometimes a hat is made by placing the covering material and buckram sheets together, and then pressing up the whole hat at once; but this can only be 35 done successfully when the covering material is of very loose texture, or the hat of a particular shape suited to this mode of manufacture. Otherwise there will always be an overlapping of body and material, and the excess of cloth will form itself into wrinkles.

40 To avoid these objections we make the crown in one piece and the brim in a separate piece, and cover each separately. Thus a sheet, *a*, of burlap, of much firmer texture than can be employed for forming a crown, *A*, and brim 45 in one piece, is cut to the proper size to form the crown, is covered with size or other cement, and a sheet, *b*, of the lining material is applied to one side, and a sheet, *c*, of the covering goods to the other side. This compound 50 sheet is then molded into a crown, *A*, Fig. 3, in any suitable machine. The brim *B* is made of three sheets, *a b c*, and molded in a similar

manner, but upon molds constructed to form a flange, *e*, round the central opening, *x*, to enter or receive the mouth of the crown-piece, 55 as shown in Fig. 1. The brim and crown are then connected by sewing or by eyelets, or otherwise, at the point where they overlap. The overlapping of the flange *e* by the crown at the band portion of the hat imparts such 60 strength at this point that material less in weight than would otherwise be required can be employed. As the brim and crown are covered separately, different materials can be employed, and can be applied more readily, 65 neatly, and with less waste than where it is necessary to cover a hat-frame having the crown and brim in one piece. In some instances the body of the crown may be made of a material that will render the use of a lining 70 unnecessary, and the brim may be covered with one coating material on the upper side and a different coating material on the under side.

We are aware that straw and other single-fabric hats have been made in two sections, 75 united at the brim, and this we do not claim; but

We claim—

1. The within-described improvement in the 80 manufacture of hats, the same consisting of forming the crown of two or more sheets of fabric, one being the body-covering material, cemented together, forming a separate brim in like manner, with an opening and flange, and 85 then overlapping the crown and flange and securing the sections together at the part where they overlap, as set forth.

2. A hat consisting of a crown-section composed of several layers of material cemented 90 together, the outer being the covering material, a separate section similarly composed, and having an opening, *x*, and a flange, *e*, that enters the crown and is secured thereto, as specified.

In testimony whereof we have signed our names to this specification in the presence of 95 two subscribing witnesses.

DWIGHT WHEELER.
DAVID C. WHEELER.
